UNITED STATES PATENT OFFICE

149,943

DESIGN FOR A MANTLE ORNAMENT OR SIMILAR ARTICLE

Ford S. Hicks, Tucson, Ariz.

Application July 3, 1947, Serial No. 140,084

Term of patent 3½ years

(Cl. D29—23)

To all whom it may concern:

Be it known that I, Ford S. Hicks, a citizen of the United States, residing at Tucson, in the county of Pima and State of Arizona, have invented a new, original, and ornamental Design for a Mantle Ornament or Similar Article, of which the following is a specification, reference being had to the accompanying drawing, forming part thereof.

In the drawing:

Figure 1 is a side elevational view of my design for an ornamental mantle ornament or similar article;

Figure 2 is a bottom plan view, and
Figure 3 is a front elevational view.

I claim:

The ornamental design for a mantle ornament or similar article, as shown.

FORD S. HICKS.
